UNITED STATES PATENT OFFICE.

JULIUS MATTSON, OF CHICAGO, ILLINOIS.

MILLING-MACHINE CUTTER.

Application filed December 21, 1922. Serial No. 608,270.

To all whom it may concern:

Be it known that I, JULIUS MATTSON, a citizen of the United States, and a resident of Chicago, in the county of Cook and State 5 of Illinois, have invented a new and useful Improvement in Milling-Machine Cutters, of which the following is a full, clear, and exact description.

My invention relates to improvements in 10 milling machine cutters, and it consists in the combinations, constructions, and arrangements herein described and claimed.

An object of my invention is to provide 15 an improvement over that form of the device disclosed in my co-pending application Serial No. 597,898, filed October 30, 1922. In said prior application I disclosed a tool plate which has cutters mounted therein, these cutters being circular and non-circular, 20 the circular cutters being adapted to do the rough cutting, and the non-circular cutters being adapted to do the finishing cutting. The present form of the device differs from the form disclosed in my co-pending application 25 Serial No. 597,898 in that the circular cutters are disposed at a different angle with respect to the work being cut than are the non-circular cutters, whereby the circular cutters can more readily do the rough 30 cutting than they could if they were disposed at the same angle as the finishing cutters, i. e., the non-circular cutters.

A further object of my invention is to 35 provide a device of the type described which has novel means for locking the cutters in adjusted position.

A further object of my invention is to 40 provide a device of the type described in which the cutters may be rotated so as to bring a different portion of their cutting edges in engagement with the work and which has means for holding the cutters in their adjusted position.

A further object of my invention is to 45 provide a device of the type described which is relatively simple in construction and which is thoroughly efficient for the purpose intended.

Other objects and advantages will appear 50 in the following specification, and the novel features of the invention will be particularly pointed out in the appended claims.

My invention is illustrated in the accompanying drawings forming part of this application, in which—

Figure 1 is a plan view of the device,

Figure 2 is a section along the line 2—2 of Figure 1.

Figure 3 is a side elevation of a portion 60 of the device, and

Figure 4 is an enlarged detail view of the cutters.

In carrying out my invention I make use of a tool plate 1 which is adapted to be secured to a mandrel 2, whereby the tool plate 65 will be rotated with the mandrel. The plate 1 is provided with a plurality of sets of slots therein. Each set comprises a slot 3, which extends at an angle with respect to the axis of the tool plate, and a slot 4, which 70 is disposed at an angle with respect to the slot 3. The slots 3 and 4 are in reality a single recess which has a radially extending side and an angularly extending side 4. The slot 3 extends inwardly so as to provide 75 a recess 5. As clearly shown in Figure 1, the tool plate 1 has threaded bores 6 and 7 therein which are disposed in a vertical plane and adjacent to the recess 5.

Cutter carrying members 8 and 9 are disposed 80 in the slots 3 and 4 and are adapted to be clamped in adjusted position by means of a wedge-shaped member 10. As clearly shown in Figure 1, the member 8 extends into the recess 5. The member 10 is provided with two bores 11 and 12 which are 85 also disposed in vertical alignment with respect to each other and are adapted to be aligned with the bores 6 and 7. Bolts 13 and 14 are disposed in the bores 11 and 12 90 and are received in threaded bores 6 and 7. The bolts 13 and 14 are provided with enlarged disc-shaped portions 15 and 16 adjacent to their inner ends. It will be noted 95 from Figure 1 that the inner ends of the bolts 13 and 14, i. e., the portions of the bolts on the inner sides of the discs 15 and 16 are threaded and are received in the bores 6 and 7. The members 8 and 9 have recesses 100 16' therein which receive the disc portions 15 and 16. A rotation of the bolts 13 and 14 will cause the portions 15 and 16 to carry the members 8 and 9 inwardly in the slot 3. In this manner the members 8 and 9 are 105 moved at will.

After the members 8 and 9 are adjusted in position, the wedge-shaped members 10 are moved inwardly so as to clamp the members 8 and 9 in adjusted position. This movement is accomplished by means of nuts 17 and 18. The members 8 and 9 are disposed at different angles with respect to each 110

other, as heretofore stated, and are adapted to carry cutters at their lower ends. The member 8 carries non-circular cutters, while the member 9 carries circular cutters. The 5 circular cutters which are carried by the member 9 are disposed at a greater angle than are the non-circular cutters which are carried by the member 8. It will therefore be seen that circular cutters are adapted to 10 more readily cut into the work than are the non-circular cutters, since the circular cutters are disposed at a greater angle than the non-circular cutters.

In Figures 3 and 4 I have shown means 15 for securing the cutters to the members 8 and 9. It will be noted from Figure 3 that the circular cutters 19 are secured to the members 9 by means of bolts 20. The bolts 20 have heads 21 which are received in the recesses in the members 9, whereby the outer surface of the heads are flush with the outer surface of the members 9. A nut 22 is mounted on the bolt 20 and when tightened causes the cutter 19 to frictionally engage 25 with the member 9. The member 9 also carries means for positively preventing the rotation of the cutter 19 on the bolt 20 after the nut 22 is once tightened. As clearly shown in Figure 4, the cutter 19 has recesses 30 23 therein, these recesses being disposed in a circle which is concentric with the axis of the cutter. The member 9 has a wedge-shaped opening 24 therein in which a tapered pin 25 is disposed. The head of the 35 pin 25 is adapted to be received in any one of the openings 23 of the member 19. When the nut 22 is tightened it securely holds the cutter in engagement with the member 9 so that the pin 25 will be received in one of 40 the openings 23 and thus hold the cutter 19 from rotation.

In like manner the non-circular cutter 26 is provided with openings 27 in which the 45 head of a tapered pin 28 is adapted to be received. The pin 28 is mounted in an opening 29 in the member 8. The cutter 26 is secured in place to the member 8 by means of a bolt 30 that has its threaded portion inserted in a threaded bore in the member 8. 50 The cutting edges of the cutter 26 are of equal length and are adapted to be swung into such a position as to be brought into engagement with the work to be cut.

From the foregoing description of the 55 various parts of the device, the operation thereof may be readily understood. The cutters 19 and 26 are secured to the members 9 and 8 by the means heretofore described, and are held in place by the pins 25 and 28 60 respectively. The cutters 19 and 26 may be adjusted with respect to the work 31 by merely moving the members 9 and 8 into the desired position. The members 8 and 9 may be moved upwardly or downwardly together 65 so as to raise or lower the cutters with re-

spect to the work. After the members 8 and 9 are moved into the position desired, they are held in place by means of the wedge-shaped member 10. This member in turn is held in place by means of the nuts 17 and 18. The circular cutters are disposed at a greater distance from the center of rotation of the tool plate 1 than are the non-circular cutters. On the other hand, the non-circular cutters are disposed in a lower plane than are the circular cutters. In this manner the circular cutters are adapted to do the rough cutting and the non-circular cutters to do the finishing cutting. It will therefore be 70 observed that the device, equipped with the cutters 19 and 26, is adapted to make a rapid cut which is smooth. The cutters 19 and 26 are provided with central bores 32 and 33 by means of which the cutters may be mounted upon the lathe so as to be sharpened. As heretofore stated, the cutters are held against rotation by means of the pins. The disposing of the circular cutters at a greater angle than the non-circular cutters provides a novel means for providing a 80 device which is adapted to make a rapid yet smooth cut. The device is extremely efficient for the purpose intended, and is not likely to easily get out of order.

I claim:

1. A device of the type described comprising a tool plate, and circular and non-circular cutters carried by said tool plate, said non-circular cutters being turned more at right angles to the direction of travel of 100 said circular cutters than the circular cutters.

2. A device of the type described comprising a tool-plate, cutter carrying members adjustably secured to said plate, and circular and non-circular cutters carried by said members.

3. A device of the type described comprising a tool plate, cutter carrying members adjustably secured to said plate, means 110 for securing said members in position, circular and non-circular cutters carried by said members and means for locking said cutters against rotation.

4. A device of the type described comprising a tool plate, cutter carrying members adjustably secured to said plate, means for securing said members in position, circular and non-circular cutters carried by 115 said members and means for locking said cutters against rotation, said last named means comprising pins carried by said members, said cutters having recesses therein adapted to receive said pins, whereby said cutters are held against rotation.

5. A device of the type described comprising a tool plate having recesses therein, two cutter carrying members disposed in each recess, the cutters in each recess extending at an angle with respect to each other, and 130

a wedge for each set of members, said wedge being adapted to hold said members in place.

6. A device of the type described comprising a tool plate having recesses therein, two cutter carrying members disposed in each recess, and means for holding said members in place, said means being adapted to forcibly eject said members when said means is removed from said plate.

10 7. A device of the type described comprising a tool plate having wedge-shaped recesses therein, two cutter carrying members disposed in each recess, a wedge for holding each set of members in place, a set screw for securing said wedge to said plate, and a disc carried by said set screw and being operatively connected to said mem-

bers so as to forcibly eject said members from said plate when said screw is removed from said plate.

8. In a device of the type described, a tool plate having wedge-shaped recesses therein, two tool carrying members disposed in each recess, and being inclined at different angles with respect to each other, a wedge for holding said members in place, a set screw for securing said wedge to said plate, a disc carried by said set screw for moving said members into or out of said recess when said set screw is actuated, and a nut carried by said set screw for forcing said wedge into engagement with said members, whereby said members are locked in place.

JULIUS MATTSON.
